Patented Dec. 28, 1971

222,781

COMBINED PLAYGROUND CLIMBER AND SLIDE

Roland W. Johnson, Hastings, Nebr., assignor to Ameri-
can Play-World, Inc., Hastings, Nebr.

Filed July 27, 1970, Ser. No. 24,153

Term of patent 14 years

Int. Cl. D21—01

U.S. Cl. D34—5

Fig. 1

Fig. 2

Fig. 3

Fig. 4

Fig. 5

FIG. 1 is a side elevational view of a combined playground climber and slide showing my new design, the opposite side being a mirror image thereof;

FIG. 2 is a top plan view;

FIG. 3 is a front elevational view;

FIG. 4 is a rear elevational view; and

FIG. 5 is a side elevational view thereof with supports showing the design as it would be mounted on the ground.

I claim:

The ornamental design for a combined playground climber and slide, substantially as shown and described.
